UNITED STATES PATENT OFFICE.

ALLSWORTH ST. CLAIR EDE, OF DUBUQUE, IOWA.

DOUBLE-ENDED FILING CABINET.

1,414,505.

Specification of Letters Patent. Patented May 2, 1922.

Application filed May 16, 1921. Serial No. 470,048.

To all whom it may concern:

Be it known that I, ALLSWORTH ST. CLAIR EDE, a citizen of the United States, residing at Dubuque, in the county of Dubuque and State of Iowa, have invented certain new and useful Improvements in Double-Ended Filing Cabinets, of which the following is a specification.

The object of this invention is to provide a filing cabinet adapted to house a series of filing cases so arranged that selected cases may be withdrawn from either end of the cabinet, thereby facilitating the use of the cabinet and enabling two users to simultaneously employ the cabinet and operate the same from opposite sides of a table, desk, or the like.

In the drawings:

Figure 1 is an end view of the cabinet showing the door lifted and the cases exposed;

Fig. 2 is a sectional view of the same partially broken away from the center;

Fig. 3 is a perspective detail showing the arrangement of one of the stops for limiting the initial movement of one of the cases;

Fig. 4 is a perspective view showing a corner of the cabinet broken away to expose the interior of the cabinet;

Fig. 5 is a perspective view of one of the cases; and

Fig. 6 is a perspective view of one of the guide rails.

The cabinet is of box formation, consisting of side walls 10, a top 11, hinged end doors 12, and a bottom 13. The top and bottom of the cabinet are provided with a plurality of upper and lower co-operating guide rails 14 extending from end to end of the cabinet, and the ends 15 of the guide rails are pointed, as best shown in Fig. 6, to facilitate the entrance of the cases into the cabinet. At each end of the series of lower guide rails, and in transverse relation to the entire series, is located a cross stop 16, as best shown in Fig. 3, which top is provided with an abrupt inner face 17 and an easy outer face 18 for a purpose now to be described, although individual stops one for each set of guide rails might be employed with equal advantage.

The cases 19 are of double faced formation, each face consisting of a single section having a back plate 20, having connected therewith side walls 21, each having along its outer edge a reversely turned inwardly

opening guide channel 22, as shown in Fig. 1, each guide channel constituting an outwardly extending reversely bent rim flange at right angles to the contiguous side wall 60 21 and in a plane parallel to the base plate 20, so that when two of the sections are secured together back to back, as indicated in Fig. 1, a center channel will be provided which rides upon the guide rail 14. The 65 channels 22 are designated to receive the hooked ends of a series of card holders 23 which carry the record cards 24, as shown in Fig. 2, the holders being slideable within the guide rails to permit of an inspection 70 and removal of the cards as occasion may require. The ends of the guide channels 22 are rounded as at 22^a to prevent scratching when in use. If desired, index plates 25 may be secured to the ends of the cases, but 75 if these are omitted, the cases may be spaced closer together and grasped for removal by engagement of the thumb and fingers with the end connecting strip 26 which overlies the contiguous edges of the abutting base 80 plates.

It will be noted from Fig. 1 that the upper guide rails 14 are positioned to afford a clearance X above each of the cases, so as to permit the latter to be slightly lifted, which 85 lifting is necessary in order to permit the proximate end of a selected case to clear the abrupt face of the adjacent cross stop, after which the case may be removed for inspection. Since the formation is uniform in 90 each end of the cabinet, a case can be removed from either end, and after inspection can be slid back into position and stopped when completely inserted by contact of its far end with the cross stop at the far end of 95 the cabinet.

As shown, the cabinet and the cases are of sheet metal formation, although obviously the parts can be constructed in whole or in part from wood, if so desired, without substantial departure from the main features 100 of the present invention.

I claim:

1. In filing devices, the combination of a cabinet provided with a series of longitudinally extending guide rails, and a cross stop at each end of the cabinet, provided with an abrupt inner face and an easy outer face, and adapted to permit a selected case to be lifted above the abrupt face and drawn over 110 the stop and removed from the near end of the case, and adapted to present its abrupt

face to stop the movement of a case inserted from the opposite end of the cabinet, substantially as described.

2. In filing cabinets, the combination of a cabinet, an upper and a lower guide rail within the cabinet in spaced relation with one another, a double faced filing case slidable between the guide rails and provided in each edge with a channel embracing the proximate guide rail, the case being formed of two sections of sheet metal secured together back to back, and each having sides extending at an angle to the back, and having the marginal edges of the sides outwardly and reversely turned to furnish card holder guides, the combined formation furnishing along each edge of the case the channel which embraces the adjacent guide rail, and card holders slidably mounted within the card holder channels, substantially as described.
3. In filing devices, the combination of a cabinet provided with spaced longitudinally extending guide rails, a case slidable upon the guide rails for removal at either end of the cabinet, a stop at each end of the cabinet

provided with an abrupt inner face and an easy outer face, the stops standing in opposed relation to each other and adapted to permit the withdrawal of the case by lifting the same above the adjacent stop and each adapted to present its abrupt face to limit the free inward movement of the case from the opposite side of the cabinet, substantially as described.

4. In filing devices, the combination of a cabinet, an upper and a lower guide rail within the cabinet in spaced relation to one another, a double faced filing case slidable between the guide rails and provided in each edge with a channel embracing the proximate guide rail, the case being formed of two sections of sheet metal secured together back to back and each having sides extending at an angle to the back and having the marginal edges of the sides outwardly turned to furnish along each edge of the case the channel which embraces the adjacent side rail, and card holders mounted within the case on opposite sides thereof, substantially as described.

ALLSWORTH ST. CLAIR EDE.
